(57) **CLAIM**

The ornamental design for an door for refrigerator with graphical user interface, as shown and described.

DESCRIPTION

FIG. 1 is a perspective view of a door for refrigerator with graphical user interface, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is an enlarged view of the encircled portion 9 in FIG.

2.

The broken lines illustrating portions of a door for refrigerator with graphical user interface form no part of the claimed design.

1 Claim, 8 Drawing Sheets
